UNITED STATES PATENT OFFICE.

SIMON TEPPER, OF BROOKLYN, NEW YORK, ASSIGNOR TO UNIVERSAL METAL SPINNING & STAMPING COMPANY, OF NEW YORK, N. Y., A CORPORATION.

DESIGN FOR A LIGHT-FIXTURE.

50,636.

Specification for Design.

Patented Apr. 17, 1917.

Application filed January 19, 1917. Serial No. 143,388. Term of patent 3½ years.

To all whom it may concern:

Be it known that I, SIMON TEPPER, a citizen of the United States, residing at New York, borough of Brooklyn, in the county of Kings and State of New York, have invented a new, original, and ornamental Design for a Light-Fixture, of which the following is a specification, reference being had to the accompanying drawings, forming part thereof.

Figure 1 is a plan view of a light fixture showing my new design; and

Fig. 2 is an elevation of the fixture partially in section.

I claim:

The ornamental design for a light fixture as shown.

SIMON TEPPER.
